[57] CLAIM

The ornamental design for an aquarium cover, as shown and described.

DESCRIPTION

FIG. 1 is a top plan view of an aquarium cover embodying my new design;

FIG. 2 is a bottom plan view thereof;

FIG. 3 is a front elevational view thereof;

FIG. 4 is an end elevational view thereof;

FIG. 5 is an enlarged fragmentary cross sectional view taken on line 5—5 of FIG. 2;

FIG. 6 is an enlarged fragmentary cross sectional view taken on line 6—6 of FIG. 1;

FIG. 7 is a top plan view of a modified form of the aquarium cover shown in FIG. 1;

FIG. 8 is a bottom plan view of FIG. 7;

FIG. 9 is a front elevational view of FIG. 7;

FIG. 10 is an end elevational view of FIG. 7;

FIG. 11 is an enlarged fragmentary cross sectional view taken on line 11—11 of FIG. 8; and

FIG. 12 is an enlarged fragmentary cross sectional view taken on line 12—12 of FIG. 7.

FIG. 1.

FIG. 2.

FIG. 3.

FIG. 4.

FIG. 5.

FIG. 6.

FIG. 7.

FIG. 8.

FIG. 9.

FIG. 10.

FIG. 11.

FIG. 12.
